UNITED STATES PATENT OFFICE.

HERBERT A. BALCOME, OF BOSTON, MASSACHUSETTS.

DESIGN FOR A MOTOR AND FAN CASE.

SPECIFICATION forming part of Design No. 29,374, dated September 20, 1898.

Application filed August 18, 1898. Serial No. 688,938. Term of patent 14 years.

To all whom it may concern:

Be it known that I, HERBERT A. BALCOME, a citizen of the United States, residing at Boston, in the county of Suffolk and State of Massachusetts, have invented and produced a certain new and original Design for a Motor and Fan Case; and I do hereby declare the following to be a full, clear, and exact description of the invention, such as will enable others skilled in the art to which it appertains to make and use the same.

Referring to the accompanying drawings, Figure 1 is a front elevation, and Figs. 2 and 3 are end elevations.

As shown in the drawings, the leading and material features of my design consist in pedestal A, surmounted by a body having a

cylindrical medial portion B and oblate spheroidal end portions C and D. Projected from the end D is a substantially spiral casting E, with a rounded periphery, ending in a tangentially-disposed cylindrical portion F.

Having thus described my invention, I claim as new and desire to secure by Letters Patent—

The design for a motor and fan case, substantially as described.

In testimony whereof I have hereunto affixed my signature in presence of two witnesses.

HERBERT A. BALCOME.

Witnesses:

T. HART ANDERSON,
HORACE VAN EVEREN.
